UNITED STATES PATENT OFFICE.

MORRIS CRUPAIN, OF NEW YORK, N. Y., ASSIGNOR OF ONE-HALF TO JACOB WOLFF, OF NEW YORK, N. Y.

POWDER-PUFF.

1,305,070.

Specification of Letters Patent. Patented May 27, 1919.

Application filed January 30, 1917, Serial No. 145,422. Renewed April 23, 1919. Serial No. 292,243.

To all whom it may concern:

Be it known that I, MORRIS CRUPAIN, a citizen of the United States, residing at New York, in the county of New York and State 5 of New York, have invented certain new and useful Improvements in Powder-Puffs, of which the following is a specification, reference being had therein to the accompanying drawing.

10 This invention relates to improvements in powder puffs, one object of the invention being the provision of an ever-ready refillable powder puff in which one member or section thereof is composed of a porous material through which the powder may be 15 dispensed as desired while the other section forms the smoothing or finishing member.

20 A further object of this invention is the provision of a powder puff forming a receptacle for the powder and being provided with a filling member that is readily insertable within the receptacle so as to be entirely concealed.

25 A still further object of this invention is the provision of a flexible powder puff forming a bag or receptacle provided with a filling member which when concealed is also a sealing member thus providing a ready means whereby the puff may be 30 filled as desired.

In the accompanying drawings:

Figure 1 is a plan view of a powder puff made according to and embodying the present invention, the filling member being extended.

35 Fig. 2 is a vertical central sectional view through the powder puff with the filling member concealed.

40 Fig. 3 is a plan view of one blank of the powder puff and also the filling member formed therewith.

Referring to the drawings, the numeral 6 designates the porous member of the powder puff, and 7 the smoothing or finishing member both of which may be of any desired 45 shape and are adapted to be sewn together to provide a bag or receptacle.

The member 6 as shown in Fig. 3, is provided with the integral portion 8 terminating in the flap or wing 9 which is adapted to 50 be formed into the filling tube 10 so that the same may assume the positions as shown in Figs. 1 and 2.

From the foregoing description it is evident that with a powder puff made according to and embodying the present invention, the same is ready for use at all times, and when empty is easily refilled, the filling member in all instances being easily extended for the filling operation and being 60 concealed within the receptacle when filled and in use.

What I claim as new is:

A powder puff comprising two sheets of material, one of said sheets being made of 65 a relatively thick soft non-porous material while the other sheet is of a porous material through which powder may be sifted, said two sheets being sewn together to constitute 70 a bag, and a tube formed from a double winged projection on the edge of the porous sheet and having its lower edge sewn to the adjacent portion of the non-porous sheet to provide a filling member for the puff, the 75 same being so flexible as to be readily reversed and inserted in the powder puff to form a closure.

In testimony whereof I affix my signature.

MORRIS CRUPAIN.
